UNITED STATES PATENT OFFICE.

GEORGE CHROMY, OF STEWART, MINNESOTA; JOSEPH CHROMY ADMINISTRATOR OF
SAID GEORGE CHROMY, DECEASED.

AUTOMATIC TRAIN-STOPPING MEANS.

1,423,396.

Specification of Letters Patent.

Patented July 18, 1922.

Application filed August 19, 1918. Serial No. 250,567.

To all whom it may concern:

Be it known that I, GEORGE CHROMY, a citizen of the United States, residing at Stewart, in the county of McLeod and State 5 of Minnesota, have invented new and useful Improvements in Automatic Train-Stopping Means, of which the following is a specification.

My present invention pertains to automatic electric means for bringing about the stoppage of two trains of a railway system in the event that two trains approach each other upon a section or block of track.

The object of my invention is to provide 15 an improved equipment appurtenant to each train and preferably located in the locomotive cab and constructed and arranged to be set in motion by the presence of another train headed in the opposite direction in the 20 same section or block, and when so set in motion to mechanically effect movement of the engineer's brake valve and the throttle valve, the former to apply the brakes and the latter to cut off the means of propulsion.

Manifestly my novel equipment is adapted 25 to operate automatically and is not dependent in any manner upon the vigilance of the locomotive engineer or a member of the crew on either train, and with the foregoing 30 in mind the best practical embodiment of my invention that I have as yet devised will be fully understood from the following description and claim when the same are read in connection with the drawings accompanying and forming part of this specification, in which:

Figure 1 is a view diagrammatic in character and illustrating two blocks or sections of track, and two locomotives bearing 40 my novel equipment.

Figure 2 is a transverse section taken through the track and showing the conductors alongside the track rails and also showing the brushes or trolleys through the medium of which electric current is transmitted from the conductors into the locomotive 45 cab and vice versa.

Figure 3 is an enlarged side elevation showing the equipment in one locomotive 50 cab.

Figure 4 is a top plan view of the same.

Similar numerals of reference designate corresponding parts in all of the views of the drawings.

55 In furtherance of my invention I arrange

alongside and preferably at the outer side of each track rail 1, a section 2 of wire, or any other material well adapted for the transmission or carriage of electric current. Each wire or conductor 2 is a mile in length 60 or of any other suitable length according to the length that it is desired for each safety block or section to have, and the contiguous ends of the adjoining conductor 2 are thoroughly insulated from each other, 65 as indicated by 3, and each conductor 2 is moreover effectively insulated or electrically isolated from the ground and also from the adjacent track rail.

Carried by each locomotive cab are current collectors 4, there being one of such collectors at each side of the cab, and each collector 4 being provided at its lower end with a trolley 5 or a suitable brush or other device adapted to travel on the adjacent conductor 2 in electric contact therewith. The current collectors 4 of each locomotive 75 equipment are arranged in a normally interrupted electric circuit with a source of electric energy 6, and a suitable electro-mechanical circuit closing device 7 as best shown in Figure 1.

When two trains equipped with my improvements are approaching each other on the same block or section of track, current 85 will pass from the plus-pole of the source of energy 6 in one cab, to the collector 4 and the trolley 5 thereof, then through one of the conductors 2, then through the trolley 5 and collector 4 at the same side of the 90 other cab, then through the relay 17 of the latter cab, and the battery 6 thereof, then through the other collector 4 and trolley 5 of said cab; then through the other conductor 2 and then through the trolley 5 95 and collector 4 of the first named cab and the relay 7 therein to the opposite side of the first named source of energy 6. It will be understood in this connection that the batteries 6 have different poles opposed to each other. When said approach takes

place the electro-magnets or analogous electro-mechanical devices in each locomotive equipment will be energized to attract an armature 8, and the said armature will 105 serve to close a major electric circuit in each cab so as to move the throttle lever and the engineer's valve in the cab and thereby automatically bring about a stoppage of the train.

2
 The brake applying and power controlling equipments of the two locomotives are similar in construction and therefore a detailed description of the single equipment shown in Figures 3 and 4 will suffice to impart a definite understanding of both. Referring therefore, to Figures 3 and 4, 9 is a source of electric energy which may be a dynamo, or any other means for furnishing an adequate supply of current. 10 is a motor arranged in a normally interrupted circuit with the source of energy 9; the said circuit being adapted to be closed by the switch 11 actuatable by the before mentioned armature 7. 12 is a capstan or winding shaft connected through gearing with the motor 10. 13 is a cable connected to and designed to be wound upon the shaft 12 and also connected to the hand lever 14 of an engineer's valve 15, and 16 is a cable connected to and designed to be wound upon the shaft 12 and also connected to the throttle valve lever 17 of the cab equipment. It will be readily understood from the foregoing that when the circuit containing the source of energy 9 and the motor 10 is completed by the means described, the shaft 12 will be rotated to take up the cables 13 and 16, and through the medium of the said cables move the engineer's valve to apply the brakes, and the lever 17 to shut off the supply of steam to the engine. It will also be understood that because of the flexible character of the cables 13 and 16, the said cables will not interfere in any measure with the ordinary manual operation of the engineer's valve and the throttle. It will further be appreciated that my novel cab equipment is simple, inexpensive and compact in construction, and that it is adapted to be readily installed in a locomotive cab such as at present in use without material alteration of the cab or the devices usually

employed as appurtenances of the engine and the brakes.

An important characteristic of my invention resides in the fact that it is operated automatically to stop both trains in the contingency stated without any attention whatsoever from any person in authority on either train. This will be appreciated as an important advantage when it is remembered that it is the human factor that generally gives rise to collisions on railway tracks.

Another important feature of my invention is that my novel equipment does not interfere in any measure with the operation of trains except in the contingency set forth.

Having described my invention what I claim and desire to secure by Letters Patent is:

In the means described for stopping a train, the combination of a railway track, electric conductors arranged alongside the track rails, and a train equipment comprising a normally interrupted circuit in which the said conductors and a circuit closer are interposed; said circuit being adapted to be completed when a similarly equipped train running in an opposite direction is in dangerous proximity on the track, a source of electric energy and an electric motor arranged in a normally interrupted circuit including said circuit closer, whereby said motor circuit will be completed by the circuit closer on the closing of the first-named circuit, and means operable by the electric motor for manipulating an engineer's valve and a throttle lever to stop the train, and including a single winding shaft and cables directly connecting said shaft with the engineer's valve and the throttle lever.

In testimony whereof I affix my signature.

GEORGE CHROMY.
